UNITED STATES PATENT OFFICE.

CHARLES B. MOORE, OF EVANSTON, ILLINOIS, ASSIGNEE, BY MESNE ASSIGNMENTS,
TO AMERICAN ARCH COMPANY, OF NEW YORK, N. Y., A CORPORATION OF DELA-
WARE.

LOCOMOTIVE-FURNACE ARCH.

1,138,041.

Specification of Letters Patent.

Patented May 4, 1915.

Application filed December 18, 1911. Serial No. 666,344.

To all whom it may concern:

Be it known that I, CHARLES B. MOORE, a citizen of the United States, and a resident of Evanston, Cook county, Illinois, have invented certain new and useful Improvements in Locomotive-Furnace Arches, of which the following is a specification.

My invention relates to improvements in locomotive boiler fireboxes and has particular reference to refractory baffles or so-called arches for installation and use in locomotive boiler fireboxes.

The general objects of my invention are to provide an arch or an arch-construction by means of which arches can be rapidly and easily built in locomotive boiler fireboxes, and particularly in such boxes as are equipped with a plurality of parallel or substantially parallel water-circulating tubes without the necessity of providing special bricks or for fitting the bricks to correspond with any slight inaccuracy of the spacing of the tubes; to provide an arch which, while adding to the firebox the desirable features of such arches, will not diminish, to any appreciable extent, the efficiency of the circulating tubes as means for transmitting the heat of the fire to the water of the boiler; to provide an arch which, when once placed in position, will be locked against displacement transversely in the firebox in all of its parts, and which will be so formed that it will materially enhance the combustion of the firebox gases.

A further object of my invention is to provide an arch for use in locomotive fireboxes which will be easy to construct and repair, and parts of which can be readily removed to give access to the flue sheet and side sheets of the firebox, when repairs to these parts are necessary, without disturbing the main portion of the arch.

My invention consists in a refractory arch for locomotive boilers having the features and fulfilling the objects above outlined together with others which will appear herein, and all as hereinafter fully described and particularly pointed out in the appended claims.

My invention will be more readily understood by reference to the accompanying drawings in which I have illustrated a loco-

motive boiler firebox equipped with an arch built in accordance with my invention and in which:

Figure 1 is a central longitudinal section of the firebox; Fig. 2 is a horizontal section of the firebox on the line 2—2 of Fig. 1; Fig. 3 is a vertical section of the firebox on the line 3—3 of Fig. 1; and Fig. 4 is a transverse section of the arch on the line 4—4 of Fig. 1.

In the actual practice of installing arches in boilers having a plurality of parallel water-circulating tubes it frequently occurs that, although the tubes are intended and supposed to be spaced regularly apart and also to be parallel, they are for one reason or another not accurate in their spacing and consequently when arch bricks which are grooved at their ends to rest upon two adjacent tubes are used, it occurs that in portions of the firebox the tubes will be too far apart to properly support the bricks and in other portions the tubes will be too close together and will consequently not allow the tubes to be positioned properly in the plane of the arch. When the tubes are too close together it necessitates the trimming of the bricks which is not only expensive but very unsatisfactory.

Among other advantages inherent in my arch is that the above difficulty is removed and if the spacing of the tubes is only fairly accurate, arches may be built in accordance with my invention as rapidly as bricks can be passed into the firebox and laid in position. Further, as the bricks of which my arch is composed do not encircle the tubes, but rest upon their upper sides or surfaces, substantially the whole of the surface of the tubes is exposed to the high temperature of the firebox gases and consequently the maximum efficiency of the tubes is developed.

My invention is capable of being used in the production of arches occupying different positions in fireboxes and having varying functions and, although I have confined the illustration of my invention to so-called "front arches," it should be understood that my invention is not thus limited.

The principal functions of front arches are to serve as baffle walls located in the path of the firebox gases as they flow from the

grate to the flues to obstruct the direct flow thereof and cause them to zigzag back and forth in the firebox thereby retaining them a sufficient time in the firebox to produce substantially complete combustion before the gases escape into the tubes and to permit the heat to pass from the gases through the walls of the firebox into the water of the boiler; and further to cause an even distribution of the heat throughout the interior surface of the firebox. Such arches are usually in an inclined position and serve to deflect the currents of gases as they rise through the firebox and cause the various strata of gases to intermix and commingle and I add to its desirable feature by providing the underside of the arch with many subsidiary gas mixing pockets and baffles which not only serve to retard and break up the flow of gases along the under surface of the arch, but also serve to cause the fuel particles and cinders carried upward by the gases to be returned to the fuel bed.

A locomotive firebox, as shown in the drawings, consists of a flue sheet 2, side sheets 3-3, a rear sheet 4 and a crown sheet 5. The firebox is provided with a grate 6 and the rear sheet is provided with a fuel door or opening 7. Flues 8 lead forward from the flue sheet and I have illustrated the firebox as being provided with a plurality of water circulating tubes 9. These tubes usually extend from the lower portion of the flue sheet rearwardly and upwardly to the upper portion of the rear sheet, and serve to increase the circulation of water between the front and rear water legs of the boiler. These tubes being situated within the firebox and exposed to the high temperature of the firebox gases, serve to increase the efficiency of the firebox in its steam-producing qualities.

I build my arches of two kinds or forms of bricks A and B, the bricks A being arch bricks proper and adapted to be laid upon and supported by the arch or water-circulating tubes, and the bricks B being what might be termed "locking bricks" in that they serve the purpose of locking the arch as a whole against transverse movement in the firebox. The arch bricks A are substantially rectangular in form and I make the individual bricks of such a length that when placed upon the tubes they will span the space between two adjacent tubes and rest at their ends upon the tubes. These bricks are limited in size by the features that they shall not be so heavy individually but that they can be handled and placed in position upon the tubes with ease. Their length is determined by the spacing of the tubes and the dimensions otherwise are determined by the features that they shall not be too large to be passed readily through the fire door of the firebox. The arch itself is built of

several parallel rows or series of these bricks, a longitudinal row or series of these bricks spanning the space between two adjacent tubes. The arch preferably abuts the flue sheet and extends rearwardly and upwardly therefrom upon the inclined portions of the arch tubes. I usually extend the arch rearwardly to about the middle of the firebox, as this length of arch results in the best distribution of heat within the firebox. The main part of the arch which is built of the bricks A is laterally co-extensive with the arch tubes 9 and I so proportion the bricks A to the spacing of the tubes that the outer edges of the arch proper lie substantially above the centers of the two outer tubes. The locking bricks B are similar to the arch bricks A in that they are rectangular in shape, but they are distinguished from the arch bricks in that they are provided on their inner ends with a socket or groove B' adapted to partly encircle the tubes upon which they rest, and they are longer than the space between the tube and the adjacent side sheet of the firebox so that when they are placed in position from above with the socketed end on the tube, they assume an upwardly and outwardly inclined position, their outer end resting against the adjacent side sheet. I make these bricks of such a length that they wedgingly engage the tube and the side. The inner or socketed ends of these bricks rest upon and extend above the tube and when these bricks are in position those inner ends form shoulders or abutments which positively retain the main or middle portion of the arch in position transversely in the firebox. I preferably arrange the bricks in transverse rows across the firebox, each row consisting of a middle portion composed of a number of arch bricks A corresponding with the spaces between the tubes, and two of the arch locking bricks B, one arranged at each end of the row. For the purpose of lightening the arch, I make the arch bricks A with large recesses or openings A' in their under sides. These recesses are nearly as large as the bricks and the bricks are thus provided with thin, depending marginal edges or walls A² and A³. The walls A² are on the transverse edges of the bricks and extend transversely of the arch on its under side and thus serve as subsidiary baffles to assist in the admixing of the firebox gases and the return of the fuel particles to the grate. The locking bricks are likewise provided with sockets or recesses B² and with marginal edges B³ which serve a like purpose. This form of arch lends itself readily to the production of arches, particularly suitable for the fireboxes in which they are built, as the various longitudinal rows of the arch bricks can be built of bricks having different shapes and by means of which the gas mixing pockets A' 130

of the different longitudinal rows of bricks may be of different depths. In Fig. 4 I have illustrated this formation of arch.

The arch illustrated comprises a middle longitudinal row C of the arch bricks and two outer rows C'. I make the middle row of bricks of such a form that the bottom walls A⁴ of these bricks are raised some distance above the tubes upon which the bricks 10 rest and I make the bricks of the rows C' of such shape that their outer ends are considerably nearer to the tubes A than near the inner ends and consequently the arch as a whole is higher in the middle of 15 the firebox than at the sides; or, in other words, the pockets A' are deeper at the middle than at the sides of the arch.

It is obvious that in fireboxes in which the arch tubes are at different heights I can 20 make the arch itself level by varying the heights of the various bricks, or I can vary the height of any portion of the arch in the same manner. The bricks themselves, being formed with recesses or pockets, and 25 the marginal walls being not reduced materially in strength, the weight of the arch itself is greatly reduced and consequently the possibility of damaging or injuring the tubes by vibration of the arch is reduced. 30 When it is desired to repair the side sheets or the flue sheet the bricks which rest upon the sheet, which is to be repaired, can readily be removed without disturbing the remainder of the arch. In order to prevent 35 the bricks of the arch from becoming fused together in such a manner that the individual bricks cannot be removed readily, I cut away the ends of the bricks in such a manner that the contacting surfaces of the adjacent 40 bricks, which lie above the tubes, are reduced to a minimum and the arch itself is provided on its upper surface with open V-shaped joints C² between the longitudinal rows of bricks. These joints are protected from the 45 severest action of the fire by the tube which lies directly beneath them and they are soon filled with cinders or ash carried over and upon the arch by the firebox gases and are thus protected against fusing or from being 50 cemented together by the slag which sometimes forms upon these arches.

As many modifications of my invention will readily suggest themselves to one skilled in the art, I do not limit or confine my invention to the specific structures herein 55 shown and described.

Having thus described my invention I

claim as new and desire to secure by Letters Patent:

1. A locomotive boiler firebox and its longitudinal inclined arch tubes, in combination with a longitudinal row of upwardly and outwardly inclined refractory bricks interposed between each side sheet of the box and the adjacent arch tube, each said brick having its lower inner end socketed upon its tube, and a refractory arch body resting upon and entirely above all said tubes with its edges in abutment with said rows of bricks and thereby held against transverse movement in the firebox. 60

2. A locomotive boiler firebox and its longitudinal inclined arch tubes, in combination with a longitudinal row of upwardly and outwardly inclined refractory bricks 65 interposed between each side sheet of the box and the adjacent arch tube, each said brick having its lower inner end socketed upon its tube, and a refractory arch body resting upon and entirely above all said tubes with 70 its edges in substantial abutment with said rows of bricks, said body being composed of inverted box-like refractory bricks presenting gas-mixing cavities in their undersides. 75

3. A locomotive boiler firebox and its longitudinal inclined arch tubes, in combination with a row of upwardly and outwardly inclined refractory bricks interposed between each side sheet of the box and adjacent tube, said bricks being wedgingly self-secured between respective tubes and side sheets, and each said brick having strengthening ribs on its upper and lower edges and presenting a cavity of general triangular shape in longitudinal section. 85

4. A locomotive boiler firebox and its longitudinal inclined arch tubes, in combination with a row of upwardly and outwardly inclined refractory bricks interposed between each side sheet of the box and adjacent tube, said bricks being wedgingly self-secured between respective tubes and side sheets, each said brick being tapered from a thick end upon the tube to a thin end against the side sheet and presenting a top of substantially uniform thickness, and strengthening ribs of substantially triangular form. 100

In testimony whereof I have hereunto set my hand this 5th day of December, 1911, in the presence of two subscribing witnesses: 105

CHARLES B. MOORE.
